CONTROL GOVERNOR FOR FLUID-
OPERATED PUMPSClarence J. Coberly, Los Angeles, Calif., assignor,
by mesne assignments, to Dresser Equipment
Company, Cleveland, Ohio, a corporation of
Ohio

Application May 5, 1947, Serial No. 746,112

14 Claims. (Cl. 103—46)

1

This invention relates to the pumping art and more particularly to a method and governing apparatus for controlling the operation of fluid-operated pumps in wells and like bodies of liquid in which the pump is immersed.

My invention has particular application to the oil industry and will be described in connection therewith, but other applications will be obvious and I do not intend to be limited to that particular usage.

In the operation of oil wells it is common practice to install in the well a fluid-operated pump having a fluid motor to which operating fluid is pumped through a supply conduit from a pumping unit situated at the ground surface, the oil from the well being forced to the surface through a production conduit usually enclosing the supply conduit so as to leave an annular passage for the well product therebetween. Such fluid-operated pumps are ordinarily operated at relatively great depth in oil wells, under conditions not observable at the ground surface, and require means for governing their rate of operation which are automatic in action and preferably situated as close as possible to the pump so as to be immediately responsive to conditions existing there. Fluctuations in the pumping load may cause the pump to race when the load lightens and to incur hydraulic shock when the load returns, and to prevent such racing, shock, and other detrimental effects, governor mechanisms may be provided in the supply conduit conveying operating fluid to the pump immediately thereabove which will control the rate of flow to the fluid motor and prevent it from exceeding a safe limit of speed.

In my Patents No. 2,119,736, issued June 7, 1938, for Governed Fluid Operated Pump; No. 2,119,737, issued June 7, 1938, for System of Operating Fluid Operated Pumps; and No. 2,266,356, issued December 16, 1941, for Automatically Governed Pump, I have disclosed governors for controlling the rate of flow of operating fluid which are responsive to variations in the pressure differential across a control orifice, such pressure differential being dependent on the rate of flow of the operating fluid through the control orifice, and in turn being related to the pump load. Such governors act responsively to the effect upon the governor produced by the racing of the pump rather than responsively to the cause for racing and, consequently, cannot be effective until racing of the pump is actually started, which may be detrimental to the mechanism of the pump or to the operation of the pumping system.

2

Various factors may affect the pump load, such as the entry of gas bubbles into the pump along with the oil, or a change in the hydraulic head or priming load on the intake side of the pump. 5 Such factors may exist simultaneously and apply cumulatively, or act individually, as when gas enters the foot of the well casing at the pump level and momentarily forces the oil in the casing upwardly. In such an event the pressure of the hydraulic head would be constant or even increase at the pump level, and yet gas instead of oil would enter the pump. To control the operation of well pumps in accordance with the pressure of the hydraulic head, I have devised a 10 governor, disclosed in my copending application Serial No. 747,233, filed May 10, 1947, in which a pilot valve is operatively connected to a member responsive to pressure in the well casing and in turn opens and closes a main valve as the 15 pressure in the casing increases and decreases within a predetermined range. Such a governor, however, is not effective to prevent racing of the pump in the event of gas entering the pump while sufficient liquid is in the casing to maintain the 20 pressure at which the pilot valve is held open, and furthermore is sensitive to surging of liquid in the well casing which may have no direct detrimental effect upon the pump, but may cause the governor unnecessarily to reduce the rate of 25 pumping. None of the devices hereinbefore referred to meets all of the operating conditions 30 hereinbefore described.

It is, therefore, a primary object of my invention to provide a method of controlling the operation of a fluid-operated pump in which the rate of operation of the pump is regulated both in accordance with the depth of the liquid in the well in which the pump is immersed, as indicated by the pressure of that liquid, and in accordance 35 with the load upon the pump, as indicated by the pressure of the operating fluid going to the pump.

It is a further object of my invention to provide a flow governing device for the operating fluid of a fluid-operated pump which is responsive both to external pressure conditions indicative of approaching detrimental operating conditions and to internal pressure conditions indicating that detrimental conditions presently exist at the pump.

It is another object of my invention to provide a governor which will gradually reduce the rate of pumping of a well pump as the liquid level in the well falls and will immediately reduce the rate of pumping if the pump begins to race.

A further object of my invention is to provide

a governor of the class described which is relatively nonresponsive to sudden surges of short duration in the liquid level of the liquid to be pumped, but is effective to maintain the liquid level at a safe operating mean.

Still another object of my invention is to provide a governor of the class described which will respond automatically to increases in the depth of the liquid to be pumped so as to increase the rate of pumping to the maximum for which the input of operating fluid is capable, and which in the event of further increase in the depth of the liquid becomes receptive to gradual increases in the rate of input of operating fluid.

Another object of my invention is to provide a governor of the class described having an orifice for controlling the flow of operating fluid which is automatically limited in area by pressure conditions in the liquid to be pumped, but which may be restricted within the limit so imposed so as to prevent an increase in flow therethrough such as might be caused by a pressure drop at the outlet of the governor, independently of the aforesaid pressure conditions.

Other objects and advantages will appear in the following specification and in the drawing, in which:

Fig. 1 is a diagrammatic view, partly in section, of my invention installed in a well;

Fig. 2 is a vertical sectional view of my invention showing the valves thereof in partly opened, or throttling, position;

Fig. 3 is a horizontal sectional view taken on the line 3—3 of Fig. 2;

Fig. 4 is a horizontal sectional view taken on the line 4—4 of Fig. 2 and on a reduced scale; and

Fig. 5 is a horizontal sectional view taken on the line 5—5 of Fig. 2 and on the same scale as Fig. 4.

Referring to Fig. 1 of the drawing, I show a well casing 19 perforated at its lower end, as is common in the art, to permit well liquid to flow thereinto from the well formation, and having a casing head 13 provided at its upper end. Suspended from the casing head 13 is a production tubing 15 having secured at its lower end an intake check valve member 22 provided with an intake opening 24 communicating with a conical pump seat 20 adapted to receive in seating relation the lower tapered end of a fluid-operated pump 18. The intake check valve member 22 is so arranged in the intake opening 24 as to permit well fluid to flow into the fluid-operated pump 18, but to prevent a reverse flow thereof. The fluid-operated pump 18 may be of any suitable type, but I prefer to use a fluid-operated pump such as shown in my above Patent No. 2,119,736, to which reference is hereby made for the details of construction thereof.

For illustrative purposes, a body of well liquid 21 is shown within the well casing 19, having a surface level 17, and it will be understood that the liquid 21 is to be pumped by the pump 18 and that the surface level 17 will vary in height above the intake opening 24 according to the relative rates of influx through the well casing 19 and of output of the pump 18.

Connected to the upper end of the fluid-operated pump 18 is an inlet tubing 16 to which is connected the flow governor 23 of my invention at a height normally below the surface level 17. Connected to the upper end of the flow governor 23 is a string of supply tubing 12 which extends through the casing head 13 to a surface pumping mechanism 11 of any suitable type.

adapted to pump operating fluid, such as clean oil, under high pressure downwardly through the supply tubing 12, the flow governor 23, and the inlet pipe 16 to the fluid-operated pump 18 to actuate the same. Also connected to the casing head 13 and communicating with the production tubing 15 is a discharge pipe 10 adapted to convey fluid discharged therethrough to a point of discharge or use (not shown).

A special coupling 14 connects upper and lower units of the production tubing 15 at the level of the flow governor 23 and has, between said upper and lower units, an inwardly extending thickened portion 38 forming a guide surface 40 of sufficient diameter to allow the pump 18 to pass downwardly therethrough to rest upon the conical pump seat 20, and fitting slidably upon a housing 34 which encases the hereinafter described members of the governor 23. Vertical passages 42 in the thickened portion 38 of the special coupling 14 connect the interiors of the upper and lower units of the production tubing 15 and permit the pump 18 to pump liquid upwardly past the housing 34.

The housing 34 comprises an upper coupling member 28 threadedly secured to the supply tubing 12, and a lower coupling member 86 threadedly secured to the inlet tubing 16, the coupling members 28 and 86 being threadedly secured to each other, and the upper coupling member 28 being externally proportioned to fit closely in the thickened portion 38 of the special coupling 14. The upper coupling member 28 has a coaxial bore 49, in the upper part of which is disposed a cylinder 33 housing a bellows member 36 of the type known as a Sylphon and longitudinally expandable and contractible in response to decrease and increase of external pressure. The lower coupling member 86 has a coaxial bore 64 housing a cylinder 74, which is proportioned externally to leave an annular passage 78 between its outer surface and the inner surface of the coupling member 86 and is threadedly secured to a downward extension 58 of the upper coupling member 28 of reduced diameter. A cylinder head 88 is threadedly secured in the lower end of the cylinder 74 and is provided with an extension 98 closely fitting within a guide collar 96 formed on the inner surface of the lower coupling member 86. The guide collar 96 serves to keep the cylinder 74 in alignment within the bore 64 to maintain uniform width of the annular passage 78.

The bellows member 36 is secured, as by soldering, to a head 29 which is threadedly secured to the cylinder 33 and to the upper coupling 28 and is provided with a nut extension 25 by which the cylinder 33 and the bellows member 36 contained therein may be detached from the housing 34 by application of a suitable wrench. The head 29 has a bore 26 forming a check valve chamber 31 in which is a ball check 30, and the bore is closed by a threaded plug 27, which may be removed to permit the bellows element 36 to be filled with gas at a desired pressure, the ball check 30 retaining the gas while the plug 27 is being replaced. At its lower end the bellows member 36 is secured, as by soldering, to a plunger 44 proportioned to provide a working space 45 within the cylinder 33 to permit expansion and contraction of the bellows member 36. The plunger 44 has secured to it a rod 51 which extends downwardly with a close sliding fit through a guide collar 53 formed on the lower face of the cylinder 33.

The lower end of the bore 49 of the upper coupling member 28 is closed by a cylinder head member 56 which forms also the head for the upper end of the cylinder 74. Fitting slidably within the lower part of the bore 49 is a hollow plunger 52 adapted to be limited in its upward movement by engagement with the cylinder 33 and in its downward movement by engagement of the plunger head 55 with the cylinder head 56, and urged toward the latter position by a spring 50 reacting against the cylinder 33. The lengths of the rod 51 and plunger 52 are such, and the expansibility of the bellows member 36 is so proportioned thereto, that the rod 51 makes contact with the inner face of the plunger 52 and holds the plunger head against the cylinder head 56 when the bellows member 36 is expanded, and may lose contact with the plunger 52 when the bellows member 36 is contracted, depending upon forces hereinafter explained tending to raise the plunger 52 in follow-up of the rod 51, with the sleeve 57 limiting the extent of such follow-up by making contact with the cylinder 33.

The cylinder head 56 is provided with an axial bore adapted to receive slidably a metering orifice member 61 formed by a sleeve extending downwardly from the lower face of the plunger 52 and having V-notches narrowing upwardly in its walls. When the plunger 52 is in contact with the cylinder head 56, these V-notches are closed by the cylinder head, and as the plunger is raised, the V-notches extend above the cylinder head into the bore 49, thus forming a variable-area metering orifice 63 opening thereinto. The walls of the upper coupling member 28 contain a plurality of vertical passages 32 leading from the supply tubing 12 to the interior of the cylinder 74 below the cylinder head 56, and a plurality of radial passages 59 leading from the bore 49 to the annular passage 78. Passage for operating fluid is thus provided from the supply tubing 12 to the annular passage 78 and regulated by the degree of opening of the variable-area metering orifice 63. High pressure operating fluid is thus brought to bear against the lower face of the metering orifice member 61, tending to raise the plunger 52 and to pass through the metering orifice 63 with a consequent pressure drop, creating a pressure differential across the orifice. The plunger 52 has a helical groove 55 formed on its outer surface and providing a restricted, two-way communication between the lower face of the plunger and the space 48 above and within the sleeve. When the space 48 and the groove 55 are filled with operating fluid, a dash-pot action is imposed on the plunger 52 retarding the movement thereof. As will be apparent, during downward movement of the plunger 52, fluid may flow from the lower end of the plunger into the space 48 at the upper end thereof through the helical groove 55. Conversely, during upward movement of the plunger 52, fluid may flow out of the space 48 at the upper end of the plunger by way of the helical groove 55.

The cylinder 74 houses a dual valve system 73 for controlling the flow of operating fluid from the annular passage 78 outwardly from the governor to the inlet tubing 16 and the pump 18. The cylinder 74 has a partition 75 which divides the interior of the cylinder into an upper bore 67 and a lower bore 77 and which has a central guide boss 65 extending upwardly therefrom into the upper bore 67 and a lower boss 79 extending downwardly into the lower bore 77. A control piston 60 is fitted slidably in the

upper bore 67 so as to be reciprocable therein, and is provided with an orifice 68 communicating through the wall of the cylinder 74 with the annular passage 78. A needle valve 70 is secured to the control piston 60 by a valve stem 62 slidably fitted within the guide boss 65, so as to be moved by the piston 60 in and out of contact with the valve seat formed by the walls of a passage 72 formed in the guide boss 79. A compression spring 66 is provided below the control piston 60 and tends to move it to the position shown in Fig. 2, to retain the needle valve 70 in its open position. The relative strengths of the springs 66 and 50 and the relative areas of the control piston 60 and metering orifice member 61 are such that a somewhat higher pressure differential is required to act on the piston 60 to move it downwardly against the resistance of the spring 66 than is required to act on the metering orifice member 61 to raise the plunger 52 against the resistance of the spring 50.

A main valve piston 80 is slidably fitted in the cylinder 74 below the partition 75 and has a sleeve 76 fitting slidably on the guide boss 79 and a valve stem 84 extending downwardly through the cylinder head 88. The guide boss 79 has a passage 81 in communication with the passage 72 and communicating with a passage 85 in the valve stem 84 and in the poppet head 89 of a main valve 91. The poppet head 89 seats on a valve seat 93 in the extension 98 of the cylinder head 88, which extension has a discharge passage 99 communicating with the inlet tubing 16. An annular valve chamber 92 encompassing the poppet head 89 is in communication with the annular passage 78 through lateral passages 90 in the cylinder head 88 and an annular space 94 between the cylinder head 88 and the guide collar 96. The valve stem 84 fits loosely within the cylinder head 88 so as to provide an annular passage 87 therebetween leading to the interior of the cylinder 74 below the main valve piston 80. A restricted orifice 82 in the piston 80 provides a fluid path from the lower side of the piston to the upper side thereof, and thence a plurality of passages 71 in the guide boss 65 lead to a valve chamber 69 annularly surrounding the needle valve 70. A spring 83, reacting against the partition 75, urges the piston 80 downwardly, tending to hold the main valve 91 closed.

It will be seen that operating fluid from the annular passage 78, that is, on the downstream side of the metering orifice 63, may flow through a flow channel comprising the annular passage 87, orifice 82, passage 71, needle valve chamber 69, and the passages 72 and 81 to the inlet tubing 16 when the needle valve 70 is open. The orifice 82 is so proportioned as to impress a pressure drop on fluid flowing therethrough, and the resulting sharp pressure gradient acting on the piston 80 raises it against the resistance of the spring 83 to cause the main valve 91 to open. As fluid flows through the orifice 82 only when the needle valve 70 is open, the needle valve acts as a pilot for the main valve 91.

As the cylinder 74 is not secured directly to the lower coupling member 86 surrounding it, but is only aligned therewith by the extension 98 closely fitting within the guide collar 96, the extension 98 is provided with an annular groove 97 and a sealing ring 95 sealing against the guide collar 96 to prevent leakage from the annular passage 78 to the inlet pipe 16 when the valves 70 and 91 are closed.

The bellows member 36, which it has been seen,

is capable of preventing the plunger 52 from rising by pushing the rod 51 thereagainst, and which therefore, it will be apparent, is capable of preventing the metering orifice 63 from opening, is operated by subjecting it externally to the pressure existing at its level in the well casing 19. The cylinder 33 is provided with a plurality of radial openings 39 communicating with an annular groove which registers with radial passages 43 in the upper coupling member 28. A relatively wide annular channel 47 is formed in the outer surface of the upper coupling member 28 with which the passages 43 communicate, and a plurality of radial passages 41 in the special coupling 14 complete the channel through which liquid in the well casing 19 may enter the cylinder 33, and the pressure in the well at the level of the passages 41 may be imposed upon the exterior of the bellows member 36. The annular channel 47 provides some leeway in the vertical placement of the housing 34 relatively to the special coupling 14, in a zone determined by placement of the pump 18 on the conical pump seat 20 and by the length of the inlet tubing 16. To isolate the passages 43 and 41 from the upper and lower units of the production tubing 15, which will contain liquid at a higher pressure than the pressure in the well casing 19, the outer surface of the upper coupling member 28 is provided with grooves 37 above and below the annular channel 47, and the grooves 37 are provided with sealing rings 35 which seal the housing 34 to the special coupling 14 while permitting relative vertical movement thereof such as would be necessary in lowering the governor 23 and the pump 18 into position or in raising them for inspection or repair. The interior of the cylinder 33 is likewise sealed from the operating pressure fluid within the space 48 by a sealing ring 46 carried by the base portion of the cylinder 33.

Before installation of the governor 23 in a well, the bellows member 36 is charged with a gas permitted by removal of the screw plug 27, following which the screw plug is replaced, as shown. The gas pressure with which the bellows member 36 is initially charged depends upon the level at which the governor 23 is to be installed in a well, as will be apparent to those skilled in the art from the following description of the operation of the governor.

In the operation of my invention, if the liquid in the well casing 19 is at a level above the radial passages 41 providing sufficient hydrostatic pressure to compress the bellows member 36 so as to lift the rod 51 from the plunger 52 and allow the latter freedom of movement, the action of the governor 23 will be controlled by the pressure differential across the metering orifice. High pressure operating fluid, pumped through the supply tubing 12 and vertical passages 32, will create a high pressure zone in the upper end of the cylinder 14, exerting an upward force against the metering orifice member 61 and a downward force against the control piston 60. The plunger 52 will be lifted by this upward force against the resistance of the spring 50, the retarding action of the fluid in the helical groove 55, and such back-pressure as exists in the annular passage 78. As the needle valve 70 is normally open, this back-pressure will be the result of operating resistance of the pump 18. Lifting the plunger 52 will open the metering orifice 63 and permit fluid to flow therethrough, creating a fluid pressure differential across that orifice. The opening of the metering orifice 63 will take place slowly be-

cause of the retarding influence of the fluid within the cylinder 57 being forced outwardly through the helical groove 55, and when the opening is sufficient to bring the pressure differential across the metering orifice 63 in balance with the spring 50 the opening movement will cease.

When the pressure in the annular passage 78 is sufficient to cause operation of the pump 18, fluid will flow to the pump through the annular passage 87, the orifice 82, and the needle valve 70. Flow through the orifice 82 will produce a pressure gradient in the flow channel thus activated, acting upon the piston 80 and tending to raise the piston and open the main valve 91 against the resistance of the spring 83. As opening the main valve 91 opens a direct passage to the pump 18 and therefore tends to reduce flow through the needle valve 70, the main valve 91 will seek a balanced position in which it is sufficiently throttled to maintain the flow through the orifice 82, which maintains it in that position. This throttled position of the main valve 91 and spring-opened position of the needle valve 70 may be called the normal operating position of these two valves, and a pressure differential across the metering orifice 63 sufficient to hold the metering orifice member 61 partly open against the spring 50 but insufficient to close the needle valve 70 may be called the normal operating pressure differential.

Now, if operating resistance to the pump 18 decreases, as might be caused by gas entering the pump instead of liquid, the pressure in the annular passage 78 will at once decrease, and the pressure differential across the metering orifice 63 will increase. The metering orifice 63 will then open slowly, responsive to the increase in the pressure differential and retarded by the required flow of fluid through the helical groove 55, thus tending to augment the flow of fluid to the pump so as to bring the pressure differential back to its previous balancing degree. If the increase in the pressure differential is temporarily sufficient to cause overbalancing of the spring 56 as it acts upon the control piston 60, it will move the needle valve 70 toward closed position and thus throttle the flow through the orifice 82 and cause the main valve 91 to move toward closed position. Throttling of the valves 70 and 91 will restrict the outflow of fluid to the pump 18 and will increase the pressure in the annular passage 78, tending to restore the pressure differential across the control valve 61 to normal. Thus all three valves 61, 70, and 91 tend to seek a stabilized position and to produce a stabilized normal pressure differential and to prevent a sudden outflow of fluid to the pump 18 such as would cause the pump to race.

On the other hand, a gradual increase in the rate of pumping is not prevented. If it is desired to increase the rate of operation of the pump 18, the rate of pumping of the surface pump 11 may be gradually increased. This will cause an increase in pressure on the high pressure side of the metering orifice 63, which will be partly translated to the low pressure side thereof as an increase in pressure in the annular passage 78 due to increased back-pressure from the pump 18, and will act partly to increase the pressure differential across the metering orifice. The increase of the pressure differential across the metering orifice 63 will cause it to open gradually so as to restore the pressure differential to normal, and this will permit an increased flow

to the annular passage 78. The increase in pressure in the annular passage 78 will increase the pressure gradient across the orifice 82 and cause the main valve 91 to open wider to permit increased flow to the pump 18 and to restore the pressure differential across the control valve 61 to normal. If the increase in the rate of pumping of the surface pump 11 is so gradual as to permit the metering orifice member 61 and valve 91 to thus act to restore the pressure differential to normal, without a sudden change sufficient to unbalance the force holding the needle valve 70 open, an increased rate of operation of the pump 18 may easily be obtained.

However, if the liquid level in the well casing 19 is so low as to place external pressure upon the bellows member 36 of less degree than will maintain the bellows member in contracted position against the internal pressure of the gas charge within the bellows member, that is to say, of less degree than an amount predetermined as representative of a satisfactory liquid level in the well casing 19, the rod 51 will be held against the upper face of the plunger 52, and freedom of action of the plunger in response to changes in the pressure differential across the metering orifice 63 will be prevented. Restrictive action of the bellows member 36 upon the degree of opening of the metering orifice 63 imposes a corresponding restriction upon the rate of supply of operating fluid from the surface pumping unit 11 which is a function of the amount that the fluid level in the well casing 19 falls below the predetermined or desired value. Under the aforesaid restrictive circumstances, an increase in the pressure differential across the metering orifice 63 will not avail to open the same, and it will not respond to tend to restore a normal pressure differential, and if the increase in pressure differential is sufficient to cause the piston 60 to move downwardly, the needle valve 70 will move toward throttling position, causing the main valve 91 to move similarly. This action will occur whether the increase of pressure differential across the control valve 61 is due to a pressure drop on the downstream side caused by decreased resistance at the pump 18, or to an increase in pressure on the upstream side caused by an attempt to increase too fast the rate of pumping.

If the liquid level in the well 19, and thereby the external pressure on the bellows member 36, falls sufficiently low, the rod 51 will push the control valve 61 to closed position against all effort of the pressure differential across the control valve to open it, and this will cut off flow of operating fluid to the pump 18 until the liquid level in the well casing 19 is restored to the desired operating level. As the bellows member 36 acts responsively to a change within a range of pressure rather than abruptly at a certain degree of pressure, and as the action of fluid in the helical groove 55 at all times presents a resistance to sudden movements of the plunger 52, a continued fall in the liquid level in the well casing 19 would result in a gradual closing of the metering orifice 63 rather than a sudden closing of the same, and the throttling action on the metering orifice would produce only a gradual increase in the pressure differential across the orifice but at an accelerating rate of increase. As the metering orifice member 61 cannot respond under the stated conditions to restore the pressure differential to normal, the pressure differential may increase to an amplitude actuating the needle valve 70 to move toward throttling position, piloting the main valve 91 also

to throttling position and thus further restricting flow to the pump 18 until a balance of inflow and outflow is obtained in the well casing 19, but normally the pump will adjust itself to the 5 changed rate of flow, and the pressure differential will remain within the limits within which the needle valve remains open. If the inflow to the well casing 19 increases and the liquid level therein rises, the bellows member 36 will remove its 10 restriction upon the metering orifice member 61, and in response to a continued rise in the liquid level will permit it to open to the maximum amount at which it can maintain a normal pressure differential across the metering orifice 63, as 15 determined by the input and outflow of operating fluid existing at the moment.

It will thus be seen that as the needle valve 70 is free at all times to act in response to forces affecting its control piston 60, it will act promptly 20 whenever called upon by those forces so as to prevent the pump 18 from racing, whether the liquid level in the well casing 19 is high or low. The metering orifice member 61 will, when permitted by the bellows member 36, act independently of it to allow an increase in flow to the pump 18 and can at all times act to restrict such flow. The bellows member 36 will prevent increases in flow to the pump when such increases are not 25 justified by existing liquid levels in the well casing 30 19 and will forestall pumping to such low liquid levels that the other members of the governor would be required to act to prevent the pump from pumping gas instead of liquid. Gas entering the well casing above the pump 18 may cause 35 surging of the liquid level and sudden changes of pressure, without creating a condition justifying response by the bellows member 36, and the effect of such sudden fluctuations is minimized by the retarding action of the helical groove 55.

40 Because of the sealed construction afforded by the sealing rings 35, the governor and the pump 18 may be drawn up to surface level through the production tubing 15 without disturbing the special coupling 14 and may be inspected, 45 paired, and returned to position. Changes in the pressure charge of the bellows element 36 may readily be made by removing the plug 27 and impressing or removing gas through the check valve chamber 31, or the cylinder 33, containing the bellows element and entraining the rod 51, may 50 be removed from the governor by unscrewing the head 29 from the upper coupling member 28, and a new unit containing a different pressure charge or including a rod 51 of different length may be 55 installed.

It will be noted that correlation of the metering orifice member 61 and the valves 70 and 91, and of the bellows element 36 and retarding helix groove 55, depends on correlation of the effective 60 areas of the various pistons, grooves, orifices, passages, and springs connected with and forming operating parts of said members, and that, for example, the correlation of the bellows member 36 to the metering orifice member 61 could be 65 changed with respect to a desired range of operation of external pressure by changing either the internal pressure of the bellows member, its rigidity, its length, or the length of the rod 51. Changes in these areas and forces required to 70 adapt my invention to various usages and operating conditions will be readily apparent to one skilled in the art, and do not depart from the spirit of my invention.

It is also to be noted that, although I have 75 described the invention in connection with a fluid-

operated pump installation in which the production tubing 15 and supply tubing 12 are concentric, making desirable a special form of coupling 14, the invention can readily be adapted by one skilled in the art for use in connection with a fluid-operated pump installation in which the production and supply tubings are side by side, such as is illustrated in my Patent No. 2,338,903, issued January 11, 1944, simply by connecting the flow governor 23 in the line of the supply tubing and omitting the coupling 14 from the production tubing. Consequently, I do not desire to be limited to the specific embodiment shown, but desire to be afforded the full scope of the following claims.

I claim as my invention:

1. In a fluid-operated pumping apparatus for use in wells, the combination of: a fluid-operated pump adapted to be submerged in well fluid in a well; supply tubing for conveying a high pressure operating fluid downwardly through the well to said pump to actuate it; production tubing for conveying the discharge from said pump upwardly through the well; governor means in the line of said supply tubing and adapted to control the rate of flow of operating fluid therethrough, said governor means including a variable-area metering orifice means adapted to provide a fluid pressure differential thereacross, a pilot valve, a main valve, means for impressing said fluid pressure differential across said pilot valve to tend to move said pilot valve, and means for operating said main valve in response to movement of said pilot valve; and means for closing said metering orifice in response to a predetermined decrease in the level of well fluid in the well.

2. In a fluid-operated pumping apparatus for use in wells, the combination of: a fluid-operated pump adapted to be submerged in well fluid in a well; supply tubing for conveying a high pressure operating fluid downwardly through the well to said pump to actuate it; production tubing for conveying the discharge from said pump upwardly through the well; governor means in the line of said supply tubing and adapted to control the rate of flow of operating fluid therethrough, said governor means including a variable-area metering orifice means adapted to provide a fluid pressure differential thereacross, a pilot valve, a main valve, means for impressing said fluid pressure differential across said pilot valve to tend to move said pilot valve, and means for operating said main valve in response to movement of said pilot valve; and means for varying the effective area of said metering orifice in response to a predetermined decrease in the level of well fluid in the well.

3. In a fluid-operated pumping apparatus for use in wells, the combination of: a fluid-operated pump adapted to be submerged in well fluid in a well; supply tubing for conveying a high pressure operating fluid downwardly through the well to said pump to actuate it; production tubing concentric with said supply tubing and for conveying the discharge from said pump upwardly through the well; collar means in the line of said production tubing and having a lateral fluid passage communicating between the interior and exterior thereof, and having a longitudinal passage communicating between the upper and lower ends thereof so as to permit said pump discharge to flow upwardly therethrough; governor means in the line of said supply tubing and adapted to control the rate of flow of operating fluid therethrough, said governor means including a variable-area metering orifice means adapted to pro-

vide a fluid pressure differential thereacross, a pilot valve, a main valve, means for impressing said fluid pressure differential across said pilot valve to tend to move said pilot valve, and means for operating said main valve in response to movement of said pilot valve; and means for closing said metering orifice in response to a predetermined decrease in the level of well fluid in the well, including means connected to said metering orifice means and communicating with the fluid pressure in said lateral fluid passage, and responsive to changes in said fluid pressure in said lateral passage to move said metering orifice means to vary the effective fluid flow area thereof.

4. In a governor for governing the rate of flow of a high pressure fluid to a fluid-operated pump adapted to be operated below the surface level of a liquid to be pumped, the combination of: means adapted to form a fluid metering orifice through which said fluid is adapted to flow so as to impress a fluid pressure differential on said orifice; pilot means adapted to move in response to variations in said fluid pressure differential; main valve means adapted to move in response to movement of said pilot means and being adapted to control the flow of said fluid through the governor; and means responsive to changes in the hydrostatic pressure exerted by said liquid on said governor for varying the effective fluid flow area of said metering orifice so as to vary said fluid pressure differential.

5. In a governor for governing the rate of flow of a high pressure fluid to a fluid-operated pump adapted to be operated below the surface level of a liquid to be pumped, the combination of: means adapted to form a fluid metering orifice through which said fluid is adapted to flow so as to impress a fluid pressure differential on said orifice, including a movable member adapted to vary the effective fluid flow area of said metering orifice so as to change said pressure differential; pilot means adapted to move in response to variations in said fluid pressure differential; main valve means adapted to move in response to movement of said pilot means and being adapted to control the flow of said fluid through the governor; and means connected to said movable member and responsive to changes in the hydrostatic pressure exerted by said liquid on said governor for moving said movable member.

6. In a device for governing the rate of flow of a high pressure fluid, the combination of: means adapted to form a fluid metering orifice through which said pressure fluid is adapted to flow so as to impress a fluid pressure differential on said orifice, including a movable member adapted to vary the fluid flow area of said orifice; a pilot valve; a pilot valve piston connected to said pilot valve; means for impressing said pressure differential across said pilot valve piston to control the movement of said pilot valve; a main valve adapted to control the volume of said fluid flowing through the device; a main valve piston connected to said main valve; means for impressing a second fluid pressure differential across said main valve piston to control the movement thereof, movement of said pilot valve being adapted to vary said second pressure differential; and means for moving said movable member in response to variations in fluid pressure exterior of the device.

7. In a device for governing the rate of flow of a high pressure fluid, the combination of: means adapted to form a fluid metering orifice through which said pressure fluid is adapted to

flow so as to impress a fluid pressure differential on said orifice, including a movable member adapted to vary the fluid flow area of said orifice; a pilot valve; a pilot valve piston connected to said pilot valve; means for impressing said pressure differential across said pilot valve piston to control the movement of said pilot valve; a main valve adapted to control the volume of said fluid flowing through the device; a main valve piston connected to said main valve; means for impressing a second fluid pressure differential across said main valve piston to control the movement thereof, movement of said pilot valve being adapted to vary said second pressure differential; and fluid pressure responsive means operatively connected to said movable member and communicating with the exterior of the device, and being responsive to variations in fluid pressure exterior of the device to move said movable member.

8. A flow governing device adapted to be installed in the line of two concentric tubings in a well, including: an outer tubular member adapted to be connected in the line of the outer of said tubings, said tubular member being provided with a lateral port communicating between the interior and exterior thereof; a tubular housing adapted to be connected in the line of the inner of said tubings and adapted to be received within said tubular member in fluid-tight relation therewith, said housing having an annular channel on the periphery thereof adapted to register with said lateral port, and having a fluid passage communicating between the interior of said housing and said channel; variable-area metering orifice means in said housing through which said pressure fluid is adapted to flow to impress a first fluid pressure differential on said orifice, including a movable member adapted to vary the effective area of said orifice; main valve means in said housing and adapted to control the flow of said fluid therethrough in response to variations in said pressure differential; and pressure-responsive means in said housing and connected to said movable member, said pressure-responsive means communicating with said fluid passage whereby a variation in the fluid pressure in said passage causes movement of said pressure-responsive means.

9. A flow governing device adapted to be installed in the line of two concentric tubings in a well, including: an outer tubular member adapted to be connected in the line of the outer of said tubings, said tubular member being provided with a lateral port communicating between the interior and exterior thereof; a tubular housing adapted to be connected in the line of the inner of said tubings and adapted to be received within said tubular member in fluid-tight relation therewith, said housing having an annular channel on the periphery thereof adapted to register with said lateral port, and having a fluid passage communicating between the interior of said housing and said channel; variable-area metering orifice means in said housing through which said pressure fluid is adapted to flow to impress a first fluid pressure differential on said orifice, including a movable member adapted to vary the effective area of said orifice; main valve means in said housing and adapted to control the flow of said fluid therethrough, said main valve means being movable in response to variations in fluid pressure differential thereacross; pilot means movable in response to variations in said first pressure differential to vary said pressure

differential across said main valve means; and pressure-responsive means in said housing and connected to said movable member, said pressure-responsive means communicating with said fluid passage whereby a variation in the fluid pressure in said passage causes movement of said pressure-responsive means.

10. In a governor for regulating the rate of flow of an operating fluid, the combination of: metering orifice means having a variable effective flow area and adapted to produce a pressure differential in response to flow therethrough; means exposed to fluid pressure obtaining exteriorly of the governor for varying the effective flow area of said metering orifice means so as to vary said pressure differential; and control valve means actuatable by said pressure differential for regulating the rate of flow of the operating fluid, said control valve means being in series with said metering orifice means so that the operating fluid flows through both said control valve means and said metering orifice means.

11. In a governor for regulating the rate of flow of an operating fluid, the combination of: a first valve adapted to produce a pressure differential in response to flow therethrough; means responsive to fluid pressure obtaining exteriorly of the governor for operating said first valve to vary said pressure differential; a second valve operable by said pressure differential; and a third valve operable in response to flow through said second valve for controlling the rate of flow of the operating fluid.

12. In a governor for regulating the rate of flow of a fluid, the combination of: a first valve adapted to produce a pressure differential in response to flow of the fluid therethrough; means exposed to fluid pressure obtaining exteriorly of the governor for operating said first valve to vary said pressure differential; a second valve in series with said first valve and operable by said pressure differential; and a third valve in series with said first valve and in parallel with said second valve for regulating the rate of flow of the fluid, said third valve being operable in response to flow of the fluid through said second valve.

13. In a governor for controlling the rate of flow of fluid, the combination of: a main valve for regulating the rate of flow of the fluid; a pilot valve in parallel with said main valve so that part of the fluid flows through said pilot valve and the remainder through said main valve; pressure actuatable means responsive to flow through said pilot valve for operating said main valve; a metering valve in series with said main and pilot valves; pressure actuatable means responsive to a pressure differential across said metering valve for operating said pilot valve; and pressure responsive means exposed to fluid pressure obtaining exteriorly of the governor for operating said metering valve.

14. In a fluid-operated pumping system for wells, the combination of: a fluid-operated pump adapted to be installed in a well; supply tubing adapted to convey operating fluid under high pressure downwardly through said well to actuate said pump; production tubing in said well and adapted to convey the discharge from said pump upwardly through the well; a fluid flow governor disposed in the line of said supply tubing and adapted to control automatically the rate of flow of said operating fluid therethrough in response to changes in rate of flow of such operating fluid to said pump; and means for controlling the operation of said governor automatically in response

15

to variations in the level of liquid in the well, including a fluid passage communicating between the interior of said governor and said liquid in the well at a point adjacent to said governor.

CLARENCE J. COBERLY.
